(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing our new design.

The outermost broken lines illustrate a display screen or portion thereof and form no part of the claimed design. The dot-dash broken lines in the graphical user interface represent the bounds of the claimed design and form no part of the
